CARVING BOARD

Emil S. Polk, Eastchester, N.Y.
(6 North St., Mount Vernon, N.Y.)

Filed Apr. 15, 1963, Ser. No. 74,449

Term of patent 14 years

(Cl. D44—1)

Fig.1

Fig.2

Fig.3

FIG. 1 is an isometric view of the upper surface of a carving board showing my new design;

FIG. 2 is an isometric view of the bottom surface; and FIG. 3 is a sectional view taken on line 3—3 in FIG. 1.

I claim:

The ornamental design for a carving board, substantially as shown.
